DESIGN FOR TUFTED CANDLEWICK TEXTILE FABRIC

Morris Mitler, New York, N. Y.

Application May 13, 1937, Serial No. 69,341

Term of patent 3½ years

To all whom it may concern:

Be it known that I, Morris Mitler, a citizen of the United States of America, residing in Manhattan, county of New York, and State of New York, have invented a new, original, and ornamental Design for Tufted Candlewick Textile Fabric, of which the following is a specification, reference being had to the accompanying drawing, forming part thereof, wherein, candlewick textile fabric showing my new design.

The figure is a plan view of a piece of tufted

The left hand portion of the drawing, as shown, represents the top of the design.

I claim:

The ornamental design for tufted candlewick textile fabric, substantially as shown and described.

MORRIS MITLER.
